ICE SKATE

Edward M. Jack, Litchfield, Conn., assignor to
 Union Hardware Company, Torrington, Conn.,
 a corporation of Connecticut

Application December 26, 1947, Serial No. 793,809

7 Claims. (Cl. 280—11.17)

1

This invention relates to the manufacture of ice skates of the so-called tubular type.

Such skates have runners to which are attached longitudinal tubes on which are mounted the heel and toe plates. Usually discrete conical supports are interposed between the tube and the shoe plates, welded to the opposite sides of the tubes and to the underside of the plates. It has also been proposed to form the tube of two parts with one-half of the support integral with each half of the tube. It has also been proposed to butt weld the lower end of the sleeve of a shoe plate to the end of a sleeve formed integrally with the tube. Each of these methods of construction has objections, such as high cost of construction, weakness, poor appearance or resulting corrosion, which I have sought to overcome by a special invention, the subject of this application.

I provide a tube which is suitably secured to the runner and in the preferred form has upstanding collars. The toe and heel plates have supports drawn downwardly, with a neck or boss closed at the bottom, inserted into said collars and welded or brazed in place. As an alternative, a neck portion may be formed as an imperforate boss drawn up from the tube so as to provide a transverse web inserted into the lower end of the conical support. The tip of the toe plate may be brazed or welded directly to the front end of the runner when used.

In the drawings, Fig. 1 is a side view and partial section of a skate embodying the preferred form of my invention.

Fig. 2 is a plan view of the same.

Fig. 3 is a fragmentary view of a part of a perforated blank from which the tube may be formed.

Fig. 4 is a fragmentary section and plan showing the joint between the conical supporting post and the tube.

Fig. 5 is a side view and partial section of the tubular member.

Fig. 6 is a top plan view of the tubular member.

Fig. 7 is a detail end view of the preferred form of tube.

Fig. 8 is a front end elevation of the skate.

Fig. 9 is a transverse vertical sectional view of the skate.

Fig. 10 is a side view and partial longitudinal section of the toe plate and support.

Fig. 11 is a transverse cross-section of the toe plate and support.

Fig. 12 is a transverse sectional view of a modification.

The runner 8 is of any suitable shape and material and may have an extension post 9 at its front end.

The tube 10 is formed in the usual manner from a single piece or blank of sheet metal 11 and may be provided with flanges 12 which are secured to the sides of the runner for instance by electric welding or brazing. The upper wall of the blank is pierced at 13 and provided with shallow upwardly drawn oval or elliptical collars 14 and 15. It is not necessary that the shape be that of a mathematical ellipse but generally the collars are of elongated shape.

To form the collar, an elongated slot 13 is first punched through the blank 11 from which the tube is to be formed. The length of this slot is a little less than the long axis of the ellipse or oval of the collar so that there is sufficient metal at the sides and ends of the slot from which the walls of the collar may be drawn. The slot is naturally narrower than the oval so that there is enough metal at the sides to draw up and form the extended sides of the collar. The collar may be formed while forming the tube and the upper edges of the collar are smoothed off by grinding or otherwise so as to provide a surface into which the neck of the post can be fitted and brazed or welded at the ends and at the extended sides of the collar. The collar is preferably of oval or elliptical shape in plan and of a width approximately equal to the horizontal diameter of the tube and of considerably greater length.

The toe plate 16 has a supporting post 17 which is formed as an integral part thereof by a drawing operation which forms a cup and leaves the bottom 18 closed. This post is of an oval or elliptical horizontal section gradually tapering downwardly and ending in a reduced neck 19 which fits snugly in the collar 14 of the tube where it is welded or brazed in place leaving no opening for water to leak into and stand in the tube and rust the runner or the tube.

The front end of the toe plate 16 may be brazed or welded to the extension 9 of the runner when used. The toe plate is preferably slightly concave longitudinally as well as transversely so as to greatly strengthen it and adapt it to the shape and pressure of the shoe.

The heel plate 20 is similarly formed and has a tapering, integrally drawn, supporting post 21 of oval or elliptical horizontal cross-section ending in a reduced neck 22 closed at the bottom 23 and fitted into the collar 15 of the tube and brazed or welded in place so as to produce a smooth finish.

The reduced neck of each supporting post telescopes in a collar on the tube so that there is a substantial area of contact for joining.

The closed lower ends of the posts 17 and 21 reinforce the joints by providing transverse walls which assist in preventing lateral collapse of the posts and tube.

In making a skate of course the blade, the tube with its collars, and the toe and heel plates with their cap-like posts are separately formed. According to the preferred order of assembly, the tube after being formed is attached to the blade. The necks of the posts of the toe and heel plates are then inserted into the collars of the tube and welded or brazed in place. The front end or tip of the toe plate is then welded or otherwise secured to the upper end of the extension of the blade when the blade has such an extension. This order of assembly is the most satisfactory one from a practical shop standpoint, but it should be understood that the broad invention is not limited except as called for by the claims.

Fig. 12 shows a modification in which the tube 10 is provided with an upwardly drawn imperforate boss 19 of horizontally elongated shape. In this case, the supporting post 17 is perforated and has a neck 25 shaped at the bottom to receive the rim of the boss 19 to which it is welded or brazed. In this form, the top of the boss 19 forms a transverse wall at the junction with the neck 25 which reinforces the tube and the post and prevents water from leaking down inside the tube.

It will be understood that the skate will be finished by polishing, plating, etc., after the parts have been assembled.

I claim:

1. An ice skate comprising a tubular body portion and a conical post portion of oval section, one of said portions having an open collar of oval section and the other portion having a neck with an imperforate transverse wall fitted and fixed in place in said collar.

2. An ice skate comprising a tubular body portion and a conical post portion of elongated horizontal section, one of said portions having an open collar of elongated section and the other portion having a neck with an imperforate trans-

verse wall at the bottom fitted and fixed in place in said collar.

3. A tubular type skate having a tube extending longitudinally and having a collar of elongated outline, the width of which is substantially equal to the diameter of the tube and a shoe plate having a conical post closed at the bottom and having a neck fitted into and secured in the collar of the tube.

10 4. A tubular type of skate having a tube extending longitudinally and having a collar of oval outline, the width of which is substantially equal to the diameter of the tube and a one-piece shoe plate having a tapered post closed at the bottom 15 and having a neck of oval section fitted into and fixed in the collar of the tube.

5. A tubular type skate comprising a tube secured to a runner and provided with upwardly extending collars and heel and toe plates, each 20 with an integral depending post terminating in a reduced, imperforate neck fitted to and fixed in one of the collars of the tube.

6. A tubular type skate comprising a tube secured to a runner and provided with shallow upwardly extending collars and heel and toe plates, each with a depending post terminating in a reduced neck fitted and secured to one of the collars of the tube and a transverse imperforate wall at the bottom of each post.

30 7. In a tubular type skate, a runner, a tubular member secured along the upper edge of the runner and a toe plate having a depending post terminating in a tubular member, one of said members having a protruding boss with a closed transverse wall and the other member having an open neck embracing said boss and secured thereto.

EDWARD M. JACK.
